UNITED STATES PATENT OFFICE.

JAMES M. COLEMAN, OF MONTREAL, QUEBEC, CANADA.

CAR-ROOF.

1,169,240.

Specification of Letters Patent.

Patented Jan. 25, 1916.

Application filed January 25, 1915. Serial No. 4,220.

To all whom it may concern:

Be it known that I, JAMES M. COLEMAN, a citizen of the United States, and resident of the city of Montreal, in the Province of Quebec and Dominion of Canada, have invented certain new and useful Improvements in Car-Roofs, of which the following is a full, clear, and exact description.

This invention relates to improvements in car roofs, and more particularly to sheet metal roofs for freight cars.

The object of the invention is to provide an improved joint between the plates forming the roof, which will permit of movement of the plates without appreciable wear and flexion, which tend to make the plate leak at the seam.

A further object is to provide a joint applicable equally well to wood sheathed or all metal roofs.

The desired results are obtained by providing intermediate the body portion of the plate and the perpendicular flange, an inclined portion arranged to slide on an inclined filler or inclined portion of a metal carline. Ample clearance is left for this movement of the plate and the carline cap.

Referring to the drawings which illustrate the invention: Figure 1 is a fragmentary side elevation of a roof constructed according to this invention. Fig. 2 is a sectional view of the seam or joint as used in wood sheathed roofs. Fig. 3 is a view similar to Fig. 2; showing the joint as in all metal roofs.

Referring more particularly to the drawings, 11 designates the roof plates which are provided at their edges with perpendicular flanges 12. Between the flanges and the body of the plate, inclined portions 13 are provided. The carline cap consists of a substantially flat top portion 14 and depending side portions 15, having laterally extending flanges 16 at the bottom. The top of the cap may be offset, as at 17, to hold the same securely centered on the filler.

In the arrangement for wood sheathed roof, shown in Fig. 2, the roof sheathing is designated 18, and the carline 19. Under the carline cap, a filler or bearing strip 20 is provided, having flat top and bottom and inclined sides 21, upon which the inclined portions 13 of the plates rest. A filler 22 is provided between the bearing 20 and the top of the cap to prevent tension of the cap holding bolt 23 distorting the cap or

pressing the flange 16 thereof too tightly down on the inclined portions 13 of the plates.

In the arrangement for all metal roofs, shown in Fig. 3, the roof plates and carline cap are formed exactly as previously described. The bearing strip 20 and filler 22 are, however, replaced by the metal carline 24, which is provided with inclined side portions 25 corresponding with the inclined edges 21 of the bearing strip, and forming a rest for the inclined plate portions 13.

It will be noted that in Fig. 2, the flanges 16 of the cap are in contact with the inclined portions 13 of the plate, but that in Fig. 3, these cap flanges are free from the plate. The reason for this is that in a wood sheathed car, the plates are so thin that any movement can be readily accommodated by flexion of the plate, whereas in the all metal roof, the heavier plates do not readily flex, and a free movement of the plate is provided for.

In the present invention, the inclined surface 21 forms an abutment against which the inclined portion of the plate bears. This to a very large extent eliminates movement of the sheets due to their momentum. In the wood sheathed car, the thin easily flexed sheets are held down on this inclined surface by the flanges 16 of the cap, and the flexion of the plates between the body and inclined portions, owing to lengthening or shortening of the roof, occurs at such a slightly bent portion of the plate that no damage is done the plate or its galvanizing. In the all metal roof, particularly of a steel frame car, there is practically no arching of the roof to be considered, but the heavier roof plates have much greater momentum and are much stiffer. For this reason, the cap flanges are left slightly clear of the inclined plate portions, so that the inclined portion at one edge of the plate may draw slightly away from its inclined supporting surface, and slide slightly up on the inclined surface of the adjacent carline. The inclined portion is normally out of contact with any other member, is perfectly drained, and therefore should have a life substantially equal to the body of the plate. The movement of the plate is very slight and there is furthermore only the weight of the car to be considered, so that friction and rubbing are very slight. Moreover, such rubbing takes place on the underside of the plate protected

from the weather, and any wear incident thereto may be disregarded.

From the foregoing description, it will be clearly seen that this invention eliminates sharp bends of the plates, tending to produce fracture, and also provides means holding the plates against movement, which would cause flexion of the plate at such bends. Any flexion of the plate which does occur is distributed over a comparatively large area, so that no crystallization of the metal occurs.

Having thus described my invention, what I claim is:—

15. In a car roof, transverse roof plates vertically flanged at their edges, supports for the edges of said plates sloped slightly from

the horizontal, sloping portions on said plates intermediate the vertical flanges and plate bodies, said sloping portions curving 20 very gradually into the plate body, and a cap mounted on the plate edge support covering the vertical plate flanges, and providing a normal clearance between said plates and said cap and having side flanges 25 sloping similarly to the plates and supported above the sloping portion of the plate.

In witness whereof, I have hereunto set my hand, in the presence of two witnesses.

JAMES M. COLEMAN.
